Attorneys.

UNITED STATES PATENT OFFICE.

EDWIN EG Mont SPOTTSWOOD, OF CINCINNATI, OHIO.

TELLER'S WINDOW.

Application filed September 2, 1926. Serial No. 133,268.

This invention relates to improvements in windows for tellers and the like, and has for an object the provision of a structure wherein a teller or other person in charge of moneys, valuables and the like and who has direct dealings with the public, may carry on such transactions without inconvenience and at the same time without danger of attack by bandits and the like.

10 Another object is to provide a window which provides unobstructed vision, and at the same time admits of ventilation and permits conversation to be held without inconvenience.

15 Another object is to provide a structure of this kind having means whereby money and papers may be passed through in either direction without exposing the attendant to a danger from gunfire or other intimidation.

20 Another object is to provide a window of this kind which may be opened for the purpose of passing large packages therethrough.

These and other objects are attained by the means described herein and disclosed in 25 the accompanying drawings, in which Fig. 1 is an elevational view of the device of my invention looking from the inside of a cashier's cage. Fig. 2 is a view taken on line 2—2 of Fig. 1.

30 In the present embodiment of the device of my invention, I utilize a window having a pane or light of bullet-proof glass, so that an attendant in charge of moneys is enabled to have an unobstructed view of those whom he is to transact business. The window is so

35 arranged as to be provided with an open space at its opposite edges, the frame within which the window is disposed, however, being arranged so as to provide a baffle for precluding thrusting an object through said

40 space, and to prevent anyone from shooting therethrough. Beneath the window is an open space which is controlled and protected by a novel, rotatable disc provided with

45 upstanding vanes, so that articles to be interchanged may be carried into or out of the cashier's cage by rotation of the disc, while at the same time a possible bandit or holdup man is unable to thrust a gun through the opening and is likewise unable to shoot through it.

In the drawing, any suitable wall structure 7 of a teller's cage is provided with an opening 8, in which is mounted a frame 9, the opposed vertical members 10 and 11 of which are substantially U-shape in cross sec-

tion. The side member 10 has an arm 12 of the channel disposed toward the outside of the cage, and a relatively shorter arm 13 disposed toward the inside of the cage. 60 The opposite side member 11 has a relatively long arm 14 disposed toward the inside of the cage and a short arm 15 toward the outside of the cage. The window or closure for the open space between the members of 65 frame 9 comprises a top 16, bottom 17 and side members 18 and also a cross member 19 spaced at a distance above the bottom member 17. The sides 18, top 9 and cross member 19 are each provided with a flange or 70 ledge 20, against which is seated a pane or light of bullet-proof glass 21.

Securing strips 22 serve to retain the glass 21 upon its seat and are fastened to the side members 18 and top 9 and cross members 9 75 and 19 respectively, by any suitable means such as the screws 23. The window is pivotally mounted at its top and bottom on pivots 28 and 29 in the frame 9 and may be moved about its pivotal mounting in one direction only for the purpose of opening the window. Referring to Fig. 2, it will be apparent that the long arms or sides 12 and 14 of the side members 10 and 11, will preclude opening of the window in a counter clockwise direction. A suitable buffer 24 serves to position the closed window in parallelism with the arms 12, 13, 14 and 15 and a latch member 25, pivotally mounted on an extended stud 26, carried by side member 18 80 may be seated in hook 27 on the frame to lock the window. Also pivot 29 extends from the bottom member of frame 9, through the bottom and cross members 17 and 19 of the window. A circular table or 90 disc 30 is pivotally mounted upon pivot 29 and is of a diameter substantially equal to the distance between side members 18 of the window. A pair of vanes 31 and 32 extend diametrically across the disc 30 and at 100 right angles to each other, the pivot 29 extending through their intersection portions. The vanes 31 and 32 extend upwardly from disc 30 and together with the disc 30 close the space between bottom member 17 and 105 cross member 19 and also effectively block the space between side members 18 between the said bottom and cross members.

From the foregoing it will be apparent that a teller or cashier standing before the 110 window on one side of wall 7 will be completely protected against gunfire or intimi-

dation by reason of the bullet-proof glass 21 and either vane 31 or 32, or both of them. At the same time he has unobstructed vision through the bullet-proof glass 21, and is 5 able to converse with anyone standing adjacent the window on the other side of the wall because of the opening between the various faces of side members 18 and the arms of the frames 10 and 11. When business 10 is to be transacted, a customer would, for example, place a check to be cashed upon the top of disc 30 between adjacent arms of the vanes 31 and 32, whereupon the cashier or teller would rotate the disc so that the 15 check would be within the cage and a baffle comprising either of the arms of vanes 31 and 32, or both of them, will be interposed between the cashier and the customer. In the same manner, the cashier may pass 20 money or papers from the inside of the cage to the customer on the outside of it.

If desired, guards 33 may be suitably secured adjacent the circumference of the disc 30. One of these guards would be disposed 25 at the left hand side of the teller and on the inside of the cage, while the other would be on the left hand side of the person transacting business through the window. As shown herein, the guards 33 may be secured 30 to the inner side or the inner faces of the longer arms 12 and 14 by any suitable means, such as screws or the like. If desired, the guards 33 may also be secured to the counters inside and outside of the cage 35 and over which such guards extend. The purpose of the guards is to form an effective shield so that there will be no direct communicating space through the opening in the window when the vanes 31 and 32 40 are disposed at angles of 45 degrees to the window.

Another effective means whereby complete protection may be attained, may be provided by securing a continuous upstanding flange 45 about the circumference of the disc 30, so that a series of compartments or trays are provided on the disc between the vanes and such flange.

When a large parcel or satchel is to be 50 passed through the window, the cashier may raise latch 25 by means of a suitable handle or knob 250, whereupon the window may be rotated to its pivotal mountings 28 and 29 and may be turned to an angle of 90 degrees 55 to its normal closed position. After the bulky article has been transferred to or from the cage, the window may be pushed in the opposite direction and again latched.

It should be noted also that ample ventilation is permitted through the space controlled by the disc 30 and the face thereof and also the spaces at the vertical sides of the window.

While I have shown but one embodiment 65 of my invention, it will be apparent that

modifications thereof may be had within the scope and spirit of this invention and the appended claims.

What I claim is:

1. In a teller's window, the combination 70 of a frame having channeled sides, each of said sides comprising arms of unequal length, an apertured, protective window pivotally mounted for rotatable movement in said frame and arranged for abutment with 75 the longer arms when the window is moved in one direction, means for locking the window in a closed position, a horizontal disc disposed at the bottom of the window, intersecting vanes extending from the disc and 80 serving as a protective closure for the aperture in the window and permitting exchange of articles through said aperture.

2. In a device of the class described, the combination of a transparent bullet-proof 85 protective window having an aperture at the base thereof, a disc revolvably mounted in said aperture and upright vanes carried by the disc and serving as a closure for the aperture in the window, rotation of the disc 90 permitting articles placed thereon to be passed through the aperture in the window.

3. In a teller's window, the combination 95 of a pivotally mounted bullet-proof protective window, a frame for the window having side members spaced from the sides of the window, a short flange on the forward edge of one side member, having clearance to permit pivotal movement of the window, a similar short flange on the rear edge of the 100 opposite side member, long flanges on the remaining edges of the side members and means to lock the window against pivotal movement, the space between the side members, flanges and the window providing for 105 passage of sound and air and serving as a shield against gunfire.

4. In a device of the class described, the combination of a pair of spaced side members having diagonally opposed long and 110 short flanges, a pivotally mounted window adapted to be rotatably moved in one direction to open the window and having a closing limit in spaced relation to the long flanges and means for locking the window 115 in a closed position.

5. In a safety window for tellers and the like, the combination of a window frame having opposed channelled side members, a window having an upper opening and a lower opening, said window being pivotally mounted in the frame and adapted to assume a closed position with its opposite vertical sides positioned within the channel portions of the side members and in spaced relation thereto, a bullet-proof glass secured in the upper opening of the window, a rotatable disc mounted at the bottom of the lower opening in said window and vertically 120 extending vanes carried by said disc and 125

serving to permit exchange of articles through said lower opening and excluding direct line movement of objects through said opening.

- 5 6. In a device of the class described, the combination of a bullet-proof protective window having an aperture at the base thereof, a disc revolvably mounted in said aperture, upright vanes carried by the disc and
- 10 serving as a substantial closure for the aperture in the window, and guard means adjacent the circumference of the disc for excluding direct line movement of objects through the aperture, rotation of the disc
- 15 permitting articles placed thereon to be

moved through the aperture in the window.

7. In a safety window for tellers and the like, the combination of a pair of spaced channels each comprising spaced arms and a transparent bullet-proof window mounted 20 between the channels and extending, at its sides, between but not contacting the arms whereby an indirect communicating passage is provided and whereby direct line movement between the window and channels is 25 precluded.

In testimony whereof, I have hereunto subscribed my name this 30th day of August, 1926.

EDWIN EGMONT SPOTTSWOOD.
